PEANUT BUTTER PACKAGE

Joseph L. Rosefield, Alameda, Calif.

Application September 25, 1935, Serial No. 42,086

1 Claim. (Cl. 99—171)

The object of this invention is to provide merchantable protective packages of edible commodities, the physical condition of which is such as to enable such commodities to be introduced into and completely fill the spaces of containers which, while structurally designed to retain their general space, will nevertheless have one or more of their walls provided by highly flexible, thin sheets of material, preferably transparent; for instance perishable viscous materials having a tendency to flow, shift their position and become deformed when left in rigid walled containers partially filled and having an air space into which the commodity may flow, such as peanut butter, consisting of a finely subdivided solid, saturated with and carried in suspension by an oil from which it tends to separate by precipitation of the solid, when space is left over the goods, thereby releasing the oil to escape by penetration of the wall of the package, or leaving the oil free to react with air or other oxygen source, to the deterioration of the goods.

Heretofore, in merchandising such commodities, it has been deemed necessary to use relatively expensive containers of glass, or tinned sheet metal, in order to exclude air and confine the oily constituent; and to resort to special measures to insure against deteriorating influence of oxygen or fermentative spores; experience having taught that whereas wrappers of paper, processed to render it impervious to air and moisture, and folded about a measured quantity of goods, were efficient for packaging butter and the like, especially where refrigeration is available, such paper and the methods followed in applying it, were wholly inadequate for preserving peanut butter.

The present invention in its broadest aspect proceeds upon the principle of enveloping commodities such as peanut butter, or like viscous materials in a hermetically sealed jacket constructed in whole or in part of impervious paper-like sheet material such as one of the cellulosic preparations, to which the peanut butter readily adheres, having inherent flexibility in a degree that permits it to conform to and remain in such intimacy of contact with the peanut butter as to at all times prevent air from entering between the peanut butter and its said jacket, especially under contraction incident to reduction in temperature; the volume of peanut butter being in such relation to the dimensions of the jacket that the jacket fits snugly and keeps the peanut butter under pressure sufficient to prevent formation of oil segregation spaces within the jacket; and the package thus formed being completely her-

metic as to air; non-penetrable to peanut oil; retentive of form in handling notwithstanding changes in temperature; and capable of receiving and retaining a neat and proper shelf appearance, as a package, and an appetizing appearance as the goods are opened and exposed to view. 5

Among the paper-like materials suitable for producing the envelopes, wrappers or outer confines (herein called jackets) for the new peanut butter package, are Cellophane (preferably moisture proof); Pliofilm and similar nitro-cellulosic materials; vegetable parchment, and the like. The jacket may be wrapped and sealed around a measured or molded body of the peanut butter or it may be preformed and have the peanut butter 10 poured or otherwise introduced into it, preferably at a temperature that causes it to flow intimately into contact with the confines of and fill the container which the jacket provides. The jacket if preformed, will be preferably sustained 15 by a suitable mold while being filled.

Sealing of the jacket, whether at the folds incident to wrapping around a body of goods or at the folds incident to closure of the mouth of a preformed envelope, may be by means of glue, 25 fusing together of the material of the jacket, application of a solvent of the jacket material to render it adhesive, etc.

The jacket will be completely filled to exclude 30 all air, which condition is favored by the adhesion naturally incident to contacting of the jacketing material by the goods, and which adhesive condition prevails to a degree that prevents formation of air pockets when the goods contract under drop in temperature. The oil saturated 35 solid constituent of goods adheres to the jacket and maintains a vacuum, under contraction, that results in dissipation of pockets for contaminating air, by normal external atmospheric pressure exerted upon the highly flexible jacket material. 40

It is intended that the rather delicate, highly flexible impervious and hermetic jacket of each unit of goods be protected by a more substantial carton-like reinforcing container of such gage 45 and structure of sheet material as to be self-sustaining and resist crushing of the jacketed unit when a quantity of such units are packed together for shipment, stacked for exposure for sale, or manipulated from producer to consumer. But 50 this reinforcing container will be such as not to interfere with the intended functioning of the highly flexible adhering, impervious and hermetic jacket.

From the foregoing it will be seen that the 55

present invention contemplates a cheap, and practical preservative package of peanut butter or like oil saturated solid, said package functioning upon the principle of hermetically checking the inward flow of contaminating air or moisture or the outward transfer by absorption or otherwise of the oily saturant of the goods; such exclusion by the highly impenetrable character of the enveloping jacket being materially favored by the high flexibility of the jacket that enables it to yield under external atmospheric pressure and prevent vacuum within it, when thermo-contraction of the goods takes place; and non-segregation of the solid constituent from the saturating oil and consequent non-escape of this fluid constituent under pressure of thermo-expansion, being also favored by ready yielding of the jacket; also by the adhesion of the goods to the jacket and prevention of separation spaces at time of thermo-contraction.

It is not necessary that flexible portions of the impervious material be employed for all confines of the envelope in immediate contact with or adherence to the area of the enveloped mass. On the contrary, the envelope may include in its structure, form-imparting stiffening members of cardboard or other material to constitute certain of the confines of the envelope, while leaving flexible and unrestrained otherwise than by marginally imposed tension certain other confines thereof, formed of the flexible impervious material, in direct presentation to and contact with sufficient areas of the plastic mass to prevent the mass drawing away from the confines and forming pockets in which oil could separate. The stiffening portion of the envelope may be in the form of a mere frame open top and bottom or it may be in the form of a tray, having a bottom and an open top; the stiffening member in each instance being preferably enveloped within the jacket and such folds or seams as may be required to hermetically conform the impervious sheet material to the stiffening material and close the jacket being formed over the stiffened confines. Finally the entire hermetic package may be introduced into any desired carton or protective covering for shipment.

In the accompanying drawing in which several embodiments of the invention are shown by way of illustration,

Fig. 1 is a view of the cartoned package with the cover of the carton in open position.

Fig. 2 is a perspective view of the hermetic package complete, minus the outer protecting carton,

Fig. 3 is a vertical longitudinal section through the hermetic package minus the protecting carton but including the tray formed of stiffened material in the envelope structure; the thickness of the flexible impervious material being somewhat exaggerated in showing the sealing folds,

Fig. 4 is a transverse section of the package shown in Fig. 3,

Fig. 5 is a transverse section showing the package with stiffening members conforming to lateral confines of the package and with the flexible impervious material in direct adherence to both the top and bottom of the package, and

Fig. 6 is a transverse section of the form shown in Fig. 5, encased in the outer protecting carton of Fig. 1.

A represents the outer carton which may be of conventional form and has no defining relation to the present invention. B represents the hermetically sealed enveloped package of the

present invention which consists essentially of the mass of the packaged goods enveloped in the thin paper-like flexible and impervious sheet material hereinbefore described, which may be wrapped about a rectangular or other molded mass of the commodity with the sealing fold 1 along lateral confines of the envelope and with any suitable form of conventional foiled closures 2 at the ends thereof. The seam 1 and the closures 2 are hermetically sealed by cementation adhesion, by solution of the material of the envelope, adhesion by fusion of the material, or other means that may be appropriate to the chemical constituency or physical properties of the envelope. The package shown in Fig. 2 may consist merely of the commodity and the thin flexible impervious envelope minus stiffening means and in contact with and adherence to the packaged mass throughout the external area thereof; or it may include any disposition of stiffening means incorporated in the envelope exemplified by either of the two stiffening means herein shown, so long as sufficient area of the flexible impervious material is in direct contact with and adherence to the mass to cause it to follow deformation of the mass incident to handling, changes in temperature or other causes and in a manner to prevent the forming of pockets between the confines of the envelope and the mass which might induce separation of oil from the material.

According to Figs. 3 and 4, the package may be reinforced by the tray-like stiffening member 3 conforming to the lateral confines 3a and bottom confine 3b of the package, but leaving free for intimate contact and adherence, the top wall 4 of the envelope so that in case of contraction of the mass, due to a drop in temperature, which contraction would manifest itself at the open side of the tray, the flexible impervious wall can follow the withdrawal of the surface of the mass and under external atmospheric pressure maintain its close adherence to the mass.

According to Figs. 5 and 6, the stiffening member may conform merely to lateral confines of the package as shown at 3a', leaving the bottom 5 as well as the top 4 free to deflect and maintain its adherence to receding surfaces of the mass, in accordance with the present invention.

While the invention has been exemplified in connection with the packaging of peanut butter, it is to be understood that it is also applicable to the packaging of not only this particular commodity, but cheese and other commodities of a greasy or an oily nature and viscous or other degree of plasticity, rendering it capable of coacting with an impervious flexible and sealable wrapper of the kind described.

I have herein described my new wrapper as being useful in the packaging and merchandising of peanut butter, cheese, etc., because these are commodities that are so difficult to confine, protect from deterioration, and attractively expose to the purchaser as to particularly emphasize the importance of the invention. But it is to be understood that the package is useful in merchandising any commodity which by reason of greater or less plasticity, viscosity or fluidity inherent in the material as a whole or in an ingredient thereof, presents a problem in the confinement and protection thereof and its attractive presentation to the consumer. It is also to be understood that the collar, tray or other open frame like defining and sustaining member with the envelope sheet spread across the opening or openings thereof

and folded and sealed into hermetic envelopment of the goods, is applicable to the confinement, preservation and merchantable presentation of goods which are deformable or fluid by reason 5 of granular or other sub-divided physical form as well as goods that are fluid by reason of viscous or liquid condition.

I claim:

10 A preservative peanut butter package, comprising a body of peanut butter having solid and fluid ingredients and a container filled by said body and having between the inner surfaces of its confines and said body, adhesive affinity which resists separation of the body from said surfaces under 15 changes in dimensions of the body; said container

having incorporated in at least its lateral confines a frame defining the perimeter of the package and the thickness thereof perpendicularly to the plane of said perimeter; and at least one confine of the said container consisting of thin, highly pliant, impervious and inert sheet material supported by said frame with sufficient fullness to enable it to bulge inwardly and outwardly under thermal changes in bulk dimensions of the contained body adhering thereto and thereby 10 preventing the development of spaces for the disengagement of the fluid constituent of the body and the accumulation of air.

JOSEPH L. ROSEFIELD. 15
